UNITED STATES PATENT OFFICE.

JOHN G. S. LINDHOLM AND ANDERS P. LINDHOLM, OF CHICAGO, ILLINOIS; SAID JOHN G. S. LINDHOLM ASSIGNOR TO SAID ANDERS P. LINDHOLM.

INSULATOR-PIN.

1,171,136.

Specification of Letters Patent.

Patented Feb. 8, 1916.

Application filed November 2, 1914. Serial No. 868,827.

To all whom it may concern:

Be it known that we, JOHN G. S. LINDHOLM and ANDERS P. LINDHOLM, citizens of the United States, residing at Chicago, in the county of Cook and State of Illinois, have invented certain new and useful Improvements in Insulator-Pins, of which the following is a specification.

Our invention relates to improvements in insulator supports, commonly known as "cross arm pins" and has for its general object to provide an insulator pin that is resilient in its coöperation with the frangible insulator (usually glass); that may be readily anchored to its support by an ordinary bolt or otherwise; and that is cheap, simple, durable, and easy of manufacture and installation.

In the drawing wherein we have illustrated two embodiments of our invention, for purposes of full disclosure, Figure 1 is a cross section showing an insulator secured to a cross-arm through the intermediary of a pin and anchorage structure embodying our invention. Figs. 2 and 3 are fragmentary perspective views of the two sections of the pin. Fig. 4 is a view similar to Fig. 1 showing a modified embodiment of the invention; Figs. 5 and 6 are views thereof, similar to Figs. 2 and 3; Figs. 7 and 8 are details showing different applications of the Fig. 4 structure.

In the drawing A indicates a telegraph-pole cross-arm or other suitable support, and B an insulator of well known type to be mounted thereon, such insulator usually being made, as shown, of glass with an internal tapered thread b. Referring first to the form shown in Figs. 1 to 3 C represents the pin and D a bolt securing said pin to the arm A. The pin shown consists of two members 5 and 6, separable on a vertical plane. Each said member constitutes a shell forming, roughly speaking, half of the pin structure and each provides a threaded stem portion 7, a body portion 8 and a base portion 9, complementary to the similar parts of the other member so that jointly the two members constitute a hollow pin-shell divided in a vertical plane traversing the longitudinal axis throughout the side walls of the pin, and having a double-thickness or interlapped base.

While a pin embodying our invention may be made by casting or otherwise, we prefer

that the structure be stamped or drawn of sheet metal, and in contour the parts have been designed with this end in view, the enumerated portions of each section merging one into the other in curves that facilitate metal drawing operation, and preserve the metal unruptured. The tapering hollow stem 7 is formed with a pressed thread for coöperation with the threaded insulator B; the body portion 8 is preferably swelled into a pear-shape to give a relatively extensive bearing at its lower end, and the base portions 9 are preferably circular in shape, so that each section has a base of substantially the full-base area. Thus, save, for an insignificant variation of contour due to the overlapping of the bases of the two members they are substantially symmetrical. The overlapping bases of the two members are apertured for the reception of the bolt D, the apertures being preferably rectangular so as to coöperate with the squared throat d of usual carriage bolt form. Specifically we prefer that the square aperture 10 in the inner base member be formed by striking out ears 11 that are bent downwardly and that may be sharpened at their lower edges to form penetrating lugs, the aperture 10' in the base of the outer section 5 being sufficiently enlarged to accommodate these lugs which project below the plane of the base seat so that they may penetrate somewhat into the wood of the cross arm A as shown in Fig. 1. Manifestly these parts may be made to inter-fit neatly so that when the members are assembled and the bolt D is tightened the two shell sections are so snugly assembled at their bases and their contacting edges contiguous to the bases that the bottom portion of the assembled structure is very rigid and strong. It will be observed that the doubling of the base thickness, and the interlocking of the two base portions, by means of the lugs 11 gives to the structure adequate strength to resist distortion of the base by strain imposed through the tightening of the bolt D.

For best embodiment of our invention the stem structure 7 should have its two sections normally separated at their adjacent edges 13, so that when the base structure is firmly and rigidly positioned the two halves of the stem structure may be yielding with respect to each other. It is our preference, as means to attaining this

resiliency of the stem structure that the contiguous side edges of the base sections be so formed that, when the assemblage and anchorage is completed, they may contact intimately through a portion of their vertical extent to a point adjacent that marked 14 in Fig. 1, and that the formation of the upper portions of the body parts 8 and stem parts 7 shall, before the insulator is applied, 5 throw them somewhat farther apart than is illustrated in Fig. 1, so that when the tapered insulator is screwed on the thread to the position shown in Fig. 1, the two upper portions of the sections are under some tension, springing, as it were, on the point 14 as a fulcrum. In this fashion the insulator-receiving threaded portion of the structure has such resilient adaptability to the insulator that at all times it holds said insulator 10 against rattling and "comes and goes" under expansion and contraction due to heat and cold, so that there is no liability to fracture of the insulator. This protection of the insulator against fracture is furthered by the formation of the thread in sheet-metal of uniform thickness, as the metallic threads themselves are, in a measure, resilient.

In practical construction we prefer that 30 the metal parts be all of non-rusting material or suitably galvanized or otherwise prepared to resist rust, and in order to permit the escape of any moisture that may enter or condense within the metal shell a drain opening 19 is preferably provided at a low point in one, or each, of the shell members.

In the installation of an insulator pin of the structure shown in Fig. 1, it will be obvious that the two shell members may be 40 assembled on the bolt and the bolt then passed through the aperture in the arm A, and it will be observed that should difficulty be met in inserting the bolt through the arm, (as is often the case in practice) 45 the open-top shell formation of the insulator enables a suitable rod or punch to be placed on the head of the bolt D and hammered to drive the bolt home, without in any way maltreating the shell. It will be observed 50 also that the lugs 11, biting into the wood (generally lengthwise of the grain), adequately prevent the pin and its bolt from turning, and if a carriage bolt with a sufficiently short squared throat 6 be employed 55 no counter-sink in the wood need be made, the mere tension on the bolt serving to force the lugs 11 into the wood fiber.

It will be apparent to those skilled in the art that many of the features of our invention are susceptible to mechanical modification without departure from the spirit of our invention, and we have shown in Figs. 4 to 8 a modified structure embodying features of our invention. This, however, without intent to limit the invention to the ex-

emplifications of our ideas herein shown, but as indicating that mechanical variations may be effected in many particulars within the spirit of the invention.

The half-shells 5' and 6', (Fig. 4) may be 70 generally similar to those shown in Fig. 1, but the fulcrum effect that gives desired resiliency to the pin-stem may be otherwise secured. For instance in Fig. 4, the walls of the sections are inwardly bossed, as at 75 14', and, preferably secured together as by a bolt or rivet 17, making the structure less dependent for its resiliency on the close interfitting of the base parts.

In lieu of the bolt D, or supplementing 80 a suitable bolt, the shell-bases 9' may have integral extensions 19 in the form of half-tubes, adapted to extend down through the aperture of the cross arm, these tube-halves 85 preferably being apertured as at 20 at different points in their length and having, preferably, lugs 21 at their bottoms, adapted easily to be up-set. The holding of the half-tubes in a suitable cross-arm hole, and the abutment of bosses 14' give the desired pin-resiliency, but preferably the interlapping of the bases of the pin sections, and the interengagement through lugs, are features 90 additionally employed. Thus, on both sides of the tube-half, each base extends in its horizontal plane, and the ends of the crotched base of the inner shell-member 6' may have downturned ears 11' to extend through openings 10" in the opposite base member. Also, if desired, the tubular structure 95 may be used as a sleeve for a smaller bolt D', so that the use of the pin structure is not confined to cross arms as shallow as the length of the sleeve, as shown in Fig. 7.

It will be observed with respect to Fig. 8, the tube halves may, on occasion be spread apart and flattened as desired, for nailing of the structure to a roof-peak or other support.

Other variations in specific embodiment 110 may, of course, be made within the scope of the appended claims.

Having described our invention, what we claim is:—

1. The combination, in a structure of the 115 character described, of two vertical sections each providing a threaded insulator-engaging portion, and each having a horizontal base portion, and means for securing said base portions together and to a support.

2. In an insulator, the combination of 120 two hollow-shell sections jointly providing an exteriorly threaded stem divided on a vertical plane and a seating base, and means to connect the base portions of the pin together and to a support, the edges of the threaded portion of the pin being separated 125 for lateral resiliency.

3. A sheet metal insulator pin comprising 130 two approximately similar sections, form-

ing a vertically divided hollow shell externally providing insulator-engaging threads and providing horizontal base portions adapted and arranged for mutual engagement and connection to a support, the confronting edges of said shell sections being separated throughout the upper portions for lateral resiliency, and said sections having adjacent the base meeting abutment portions forming a fulcrum.

4. The combination of a sectional, metallic insulator pin comprising two vertical sections jointly forming a hollow shell having external insulator-engaging means, said sections having overlapped base portions, one said base portion having an aperture and the other having parts to interlock with said apertures.

5. In a device of the character described the combination of two sections each providing a peripheral threaded portion, and a horizontal base portion, said base portions overlapping and having registering apertures; and a bolt taking through said apertures to secure said base structures together and to a support.

6. In a structure of the character described the combination of two hollow, sectional shell-members jointly providing a peripheral structure having a threaded tapering stem, and a pear shaped body, said members having horizontal base portions, and means for securing said members together and to a support.

7. In a structure of the character described the combination of two hollow, sectional shell-members jointly providing a peripheral structure having a threaded tapering stem, and a pear shaped body, said members having overlapping base portions, one of said sections having a drain aperture near its base, and means for securing said members together and to a support.

8. In a structure of the character described the combination of two sheet-metal shell-sections each providing a substantially circular base, the one adapted to overlie the other, said bases having apertures therein to receive a vertical bolt, the confronting

vertical edges of said shell members meeting through the lower portions only of their extent and resiliently separated adjacent their upper portions, said upper portions provided with insulator engaging means.

9. A sectional, metallic insulator pin comprising vertical sections having overlapping, horizontal base portions apertured to receive a vertical bolt.

10. A sectional, metallic insulator pin comprising vertical sections having overlapping, horizontal base portions apertured to receive a vertical bolt, one base portion having lugs interfitting in an aperture of the other base portion.

11. A sectional, metallic insulator pin comprising vertical sections having overlapping, horizontal base portions apertured to receive a vertical bolt, edge portions of the aperture in one base portion projecting through the aperture in the other to form protruding anchorage-lugs.

12. The combination of a support having an aperture, an insulator pin comprising two vertical shell sections having apertured bases, a bolt taking through said apertures, and into the pin-shell, securing said sections together and to the support, said pin sections being provided with tapered external threads near the top, and resiliently separated, and a taper-threaded insulator screwed on said pin holding said sections normally under tension.

13. In an insulator pin, the combination of two vertical sections adapted for connection with a support, each said section comprising a hollow half-shell of sheet metal externally threaded, the contiguous edges of said half-shells separated throughout their upper portion and meeting at their lower portions, and each providing a substantially horizontal base-part.

In testimony whereof we hereunto set our hands.

JOHN G. S. LINDHOLM.
ANDERS P. LINDHOLM.
